US00D637641S

(12) **United States Design Patent**
Lim et al.

(10) **Patent No.:** US D637,641 S
(45) **Date of Patent:** ** May 10, 2011

(54) **PROJECTOR**

(75) Inventors: **Jae Won Lim**, Seoul (KR); **Woo Suk Park**, Jeonbuk (KR); **Jong Chul Kim**, Gyeonggi-do (KR); **Hye Young Hong**, Seoul (KR)

(73) Assignee: **LG Electronics Inc.**, Seoul (KR)

(**) Term: **14 Years**

(21) Appl. No.: **29/360,994**

(22) Filed: **May 4, 2010**

(30) **Foreign Application Priority Data**

Nov. 12, 2009 (KR) 30-2009-0049797

(51) LOC (9) Cl. **16-02**

(52) U.S. Cl. **D16/230**; D16/225

(58) **Field of Classification Search** D16/205, D16/208, 221, 225, 230-231, 234; D21/514; 353/115, 119, 122

(57) **CLAIM**

The ornamental design for a projector, as shown and described.

DESCRIPTION

FIG. 1 is a top, front, perspective view of a projector showing our new design;

FIG. 2 is a front view thereof;

FIG. 3 is a rear view thereof, where the broken lines showing portions of a projector are included for the purpose of illustrating environmental structure and form no part of the claimed design;

FIG. 4 is a left side view thereof;

FIG. 5 is a right side view thereof;

FIG. 6 is a top view thereof; and,

FIG. 7 is a bottom view thereof.

1 Claim, 4 Drawing Sheets

FIG. 1

FIG. 2

FIG. 3

FIG. 4

FIG. 5

FIG. 6

FIG. 7
